[57] **CLAIM**

The ornamental design for a barbecue, substantially as shown and described.

DESCRIPTION

FIG. 1 is a front elevational view of a barbecue showing our new design;

FIG. 2 is a top plan view thereof;

FIG. 3 is a bottom plan view of the barbecue lid;

FIG. 4 is an enlarged cross-sectional view taken along line 4—4 of FIG. 1;

FIG. 5 is a side elevational view of the barbecue bowl;

FIG. 6 is a top perspective view of the barbecue bowl;

and

FIG. 7 is a bottom perspective view of the barbecue lid. FIGS. 3, 5, 6 and 7 show the lid and bowl separately for clarity of illustration only.

The pattern shown underneath the grill in FIG. 6 represents a screen.

FIG. 1
